Patented Oct. 3, 1922.

Inventor
Chas. C. Gibson.

Herbert S. Buick

Attorney

UNITED STATES PATENT OFFICE.

CHARLES C. GIBSON, OF DAVENPORT, WASHINGTON.

WRENCH.

Application filed October 18, 1921. Serial No. 508,549.

To all whom it may concern:

Be it known that I, CHARLES C. GIBSON, a citizen of the United States, residing at Davenport, in Lincoln County and State of Washington, have invented certain new and useful Improvements in Wrenches, of which the following is a specification.

My invention relates to improvements in wrenches of the clutched head, reversible 10 ratchet, interlocking jaw handles type, in which the jaws are adjustable longitudinally of the handle of the tool and the shanks that are rigid with the jaws are adjustable transversely of the head along lines extending 15 diagonally through the head. The primary object of the invention is the provision of a wrench of this type which may be either manually adjusted or adjusted through the manipulation of a screw for 20 properly locating the gripping jaws of the wrench.

To this end the invention consists in certain novel combinations and arrangements of the jaws and their shanks in the ratchet 25 head, and other connections, as will be hereinafter more fully pointed out and claimed.

In the accompanying drawings I have illustrated one complete example of the physical embodiment of my invention where- 30 in the parts are manually adjusted, and a modified construction thereof wherein the jaws are screw-adjusted, and the parts com- 35 bined and arranged according to the best modes I have thus far devised for the practical application of the principles of my invention.

Figure 1 is a side view of a ratchet wrench embodying my invention.

Figure 2 is a top plan view of the wrench, 40 partly broken away to illustrate the reversible spring pressed ratchet, and from which the shanks and their jaws are omitted for convenience of illustration.

Figure 3 is a longitudinal sectional view 45 through the wrench as illustrated in Figure 2.

Figure 4 is a perspective view of one of the shanks with its slid able jaw.

Figure 5 is a transverse sectional view 50 through the ratchet head showing a modified form of exterior screw nut for adjusting the jaws.

Figure 6 is a plan view showing the ratchet head of Figure 5, and the relation 55 of the two shanks thereto.

In the preferred form of the invention as

illustrated in Figures 1 through 4 of the drawings, the wrench or tool which is of the ratchet type is provided with the usual handle 1, which is formed with a side plate 2 and a detachable complementary plate 3, secured to the handle by screw 3^a. These complementary plates are provided with open, circular rings 2' and 3' to receive the ratchet head 4, which is cylindrical in shape and provided with a central annular, exterior row of ratchet teeth 5, and by means of this row of teeth the head is retained between the two rings 2' and 3' in order that it may be turned bodily when it is rigidly held with the handle 1. A spring pressed detent 6 is provided with a ratchet tooth 7 that engages the ratchet teeth on the head, and this detent is encased within the socket 8 extending longitudinally of the handle plate 2, a spring 9 being interposed in the socket to urge the detent into engagement with the ratchet head. The detent has a stem 10 passing through the coiled spring and a button or head 11 at its end by means of which, when the detent is withdrawn against the pressure of spring 9, the detent may be turned on its axis to cause the ratchet tooth 7 to engage the opposite faces of the ratchet teeth 5 when the movement of the handle 1 is reversed to reverse the movement of the wrench.

As seen in Figure 3 the ratchet head is provided with a pair of transversely extending sockets 12 and 13 disposed diagonally of the head and crossing or intersecting on different planes. These sockets are open end passages extending through the opposite sides of the head, and are designed to receive and retain a pair of complementary, 95 slidably adjustable shanks 14 and 15 crossed as indicated in Figure 1. Each of the shanks has a rack face 16 and the pair of shanks have complementary jaws 17 17' opposed to one another and adjustable toward 100 and away from each other to adapt them for different sizes of bolts or nuts or other objects. The crossed shanks are arranged with their rack faces toward the axial center of the ratchet head and the rack teeth of these rack faces are disposed obliquely of the respective shanks with the teeth of the crossed shanks in engagement at the point of intersection.

Thus by grasping the two jaws, or the two 110 opposite ends of the shanks, in the hands, the shanks may be pushed or pulled trans-

versely of the ratchet head for adjusting the distance between the two jaws. This action causes each shank to move through its socket with the teeth of the respective faces on the shanks interlocking and sliding into engagement across the diameter of the head. While the shanks pass diagonally through the head, the resulting movements are synchronous, and the pair of jaws are either separated and moved away from the head, or brought toward one another and toward the head, for proper adjustment of the jaws.

If desired, friction members as 18 may be threaded into complementary sockets in the walls of the sockets 12, 13 to engage faces of the shanks, and the interlocked relation of the rack faces of the shanks, when pressure is applied by turning the wrench, will prevent slipping of the jaws after they have been adjusted.

In Figures 5 and 6 the shanks 14' and 15' may be adjusted by turning the screw-nut 19 that is retained in the ratchet head 4' by a screw 20, the screw nut en-

gaging the rack faces 16 of the shanks to move them transversely of the head in manner similar to the manual adjustment in the preceding figures of drawing.

What I claim and desire to secure by Letters Patent is:—

1. The combination in a wrench with its head having transversely disposed, crossed socket-openings therethrough, of a pair of slidably adjustable, complementary shanks in said socket-openings having opposed jaws, and complementary co-acting rack faces on adjoining faces of said adjustable shanks.

2. The combination in a tool as described with its head having crossed socket-openings extending therethrough, of a pair of crossed, slidably adjustable, complementary shanks in said socket-openings having opposed jaws, and rack teeth on adjoining faces of said shanks in frictional engagement at the point of intersection of said shanks.

In testimony whereof I affix my signature.

CHARLES C. GIBSON.
